(57) **CLAIM**

The ornamental design for a mobile phone case, as shown and described.

DESCRIPTION

FIG. 1 is a perspective view of a mobile phone case showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof in a condition that a mobile phone has been inserted into the case.

The broken line showing of a mobile phone in FIG. 8 is included for the purpose of illustrating environment and forms no part of the claimed design.

1 Claim, 7 Drawing Sheets
